UNITED STATES PATENT OFFICE.

SAMUEL BAUMAN, OF SANTA CRUZ, CALIFORNIA.

TAG-HOLDER.

SPECIFICATION forming part of Letters Patent No. 417,852, dated December 24, 1889.

Application filed July 31, 1889. Serial No. 319,323. (No model.)

To all whom it may concern:

Be it known that I, SAMUEL BAUMAN, of Santa Cruz, county of Santa Cruz, State of California, have invented an Improvement 5 in Ticket-Holders for Piece-Goods; and I hereby declare the following to be a full, clear, and exact description of the same.

My invention relates to a device for marking goods in dry-goods stores, such as are 10 known as "piece-goods."

I term my device a "ticket-holder;" and it consists of a plate folded to fit the end of the board upon which the goods are rolled, and having straps or slots in which the ticket or 15 card may be slipped.

Referring to the accompanying drawings for a more complete explanation of my invention, Figure 1 is a view of my ticket-holder, showing its application to the board. Fig. 2 20 is an end view of the same.

What are known as "piece-goods" are usually rolled upon boards, and, being laid upon the shelf with the ends presented to the front, it is difficult to properly mark the goods so 25 that their price, number, &c., may be readily seen at a glance. In order to overcome this difficulty, I have shown a plate A, which in the present case is shown as having the sides 30 triangular in shape, and it is folded so as to just slip over the end of the board B upon which the goods are to be rolled. This plate may be held upon the board by any suitable means, either by making it fit tight, or, as shown in the present case, by the formation 35 of spurs C by punching out a tongue in the plate, so that the spur will engage and hold the wood of the board B, thus preventing the plate from slipping off. At the point where

this plate is folded over the end of the board slots are made, forming tongues D, which are raised so as to admit the ticket or slip E, upon which the necessary figures and words are printed. This ticket slips into the space beneath the strips D, and the ends are passed through slots, formed at F, at each end of the 45 plate, so that the strip is held in place. Upon these slips E are printed the matter that is necessary to identify the goods, giving number, price-mark, &c., and these slips are easily introduced and removed at will. When the 50 goods lie upon the shelves, these slips are permanently exposed, so that they can be easily read at a glance. Additional advantage derived from the employment of this folded plate A is that the plate upon the end of the 55 board stiffens and strengthens it, and prevents it from being split or broken, which often occurs in the handling of goods.

Having thus described my invention, what I claim as new, and desire to secure by Letters 60 Patent, is—

The ticket-holder herein described, consisting of a bent or folded plate having its front slotted and provided with raised tongues for the reception of a ticket and having its sides 65 formed integral with the front, said sides being triangular in form and parallel with each other and provided with spurs, which are formed by striking out a portion of said sides, substantially as described.

In witness whereof I have hereunto set my hand.

SAMUEL BAUMAN.
